JESSE D. TUCKER, OF SACRAMENTO, CALIFORNIA, ASSIGNOR TO TUCKER BROTHERS MANUFACTURING COMPANY, OF SACRAMENTO, CALIFORNIA, A COPARTNERSHIP.

SPOKE-TIGHTENING SHIM.

1,422,633.

Specification of Letters Patent. Patented July 11, 1922.

Application filed February 27, 1922. Serial No. 539,661.

To all whom it may concern:

Be it known that I, JESSE D. TUCKER, a citizen of the United States, residing at Sacramento, county of Sacramento, State of California, have invented certain new and useful Improvements in Spoke-Tightening Shims; and I do declare the following to be a full, clear, and exact description of the same, reference being had to the accompanying drawings, and to the characters of reference marked thereon, which form a part of this application.

This invention relates to improvements in devices for tightening up the wooden spokes of vehicle wheels, especially those of automobiles and is particularly an improvement over that type of tightener shown in my pending application for patent filed September 12th, 1921, Serial No. 500,150.

The principal object of the present invention is to construct a shim for the above named purpose in such a manner that when once positioned, it will not become displaced by vibration, etc., even if the spoke should shrink away from the shim.

This is accomplished by providing the shim with means for engaging the wood of the felly, which while positively preventing further movement of the shim once it is squeezed between the felly and spoke, may at the same time yield somewhat in entering the wood, if hard spots in the latter should be encountered.

Another object is to construct the shim so that the above defined wood engaging means may be made integral with the shim, and in such a manner that the entire device may be stamped at one operation from ordinary sheet metal.

A further object of the invention is to produce a simple and inexpensive device and yet one which will be exceedingly effective for the purposes for which it is designed.

These objects I accomplish by means of such structure and relative arrangement of parts as will fully appear by a perusal of the following specification and claims.

In the drawings similar characters of reference indicate corresponding parts in the several views.

Fig. 1 is a perspective view of my improved type of shim, looking at one face thereof.

Fig. 2 is a similar view, looking at the other face.

Fig. 3 is a fragmentary outline of a spoke and felly, showing my improved shim when in position.

Fig. 4 is a perspective view of a modified form of shim, looking at one face thereof. 60

Fig. 5 is a similar view, looking at the other face.

Referring now more particularly to the characters of reference on the drawings, the numerals 1 and 2 denote the component parts of the shim shown in Figs. 1, 2 and 3, the members being symmetrical and of the same size, each being shaped as a flat semi-circular washer with the cut edges lying in the diametrical line of the center of the member. The members are adapted to be substantially abutted along their edges of separation when in position, and will then include a central orifice 3 adapted to snugly surround the tenon 4 of a spoke 5, while the members 1 and 2 seat between said spoke and felly 6.

Each of the members 1 and 2 is provided with oppositely disposed and integrally formed prongs 7, these being stamped so as to lie at an acute angle to the face of the member and lying in a plane substantially at right angles with the transverse cut edges thereof; the outer and preferably pointed ends of the prongs facing away from said edges and being cut free of the shim, the only area of connection therewith being at the opposite ends.

These prongs therefore form barbs acting to prevent movement of the shim members away from the tenon once they are positioned thereabout, as shown in Fig. 3, since they bite into the wood of the felly and prevent movement of each member in the only direction that it could move. 95

The shims themselves being of somewhat thin metal, and the prongs being free at one end, allows the latter to yield in the event that the hardness of the wood of the felly prevents them from sinking therein for 100 their full and normal depth, so that they automatically accommodate themselves to the conditions encountered.

In the modified type of shim shown in Figs. 4 and 5, the shim structure consists of 105 a single member 8 in the shape of a horseshoe, being thus provided with an opening 9 from one edge leading to the central orifice 10, which fits about the tenon of the spoke.

Stamped from the shim on opposite sides 110

of the opening 9 are barbs 11, positioned to lie parallel to said opening, and with the outer or free ends facing away from the outer end of said opening. These barbs, 5 like the prongs 7 are yieldable under pressure so as to accommodate themselves to different hardness of wood encountered, and when biting into the wood act to prevent the 10 shim from movement away from the tenon 10 about which it is placed.

It will be readily seen that the shims and the prongs incorporated therewith may easily be stamped at one operation from ordinary sheet metal and with a very simple die.

15 From the foregoing description it will be readily seen that I have produced such a device as substantially fulfills the objects of the invention as set forth herein.

While this specification sets forth in detail 20 the present and preferred construction of the device, still in practice such deviations from such detail may be resorted to as do not form a departure from the spirit of the invention, as defined by the appended 25 claims.

Having thus described my invention, what I claim as new and useful and desire to secure by Letters Patent, is:—

1. A spoke tightening shim comprising a 30 flat member adapted to be placed about the

tenon of a spoke, and yieldable prongs punched from the shim and projecting beyond one face thereof.

2. A spoke tightening shim comprising a flat member adapted to be placed about the 35 tenon of a spoke, and prongs punched from the shim and projecting beyond one face thereof, the prongs projecting at an acute angle from one face of the shim and the outer ends thereof facing in the direction toward 40 which the shim must be moved to withdraw the same from about the tenon.

3. A spoke tightening shim comprising a flat member adapted to be placed about the 45 tenon of a spoke, and prongs punched from the shim and projecting beyond one face thereof, the prongs projecting at an angle from one face of the shim and being disconnected therefrom except at one end.

4. A spoke tightening shim structure comprising a pair of separated and independent members adapted to abut and to then surround the tenon of a spoke, and prongs on each side of each member projecting from one face thereof, and at an angle thereto, 50 the outer ends of the prongs facing away from the abutting edges of the members.

In testimony whereof I affix my signature.

JESSE D. TUCKER.
